UNITED STATES PATENT OFFICE.

JOSEPH REDLINE, JR., OF ROHRSBURG, PENNSYLVANIA.

SAW-MILL DOG.

SPECIFICATION forming part of Letters Patent No. 290,355, dated December 18, 1883.

Application filed October 6, 1883. (No model.)

To all whom it may concern:

Be it known that I, JOSEPH REDLINE, Jr., a citizen of the United States, residing at Rohrsburg, in the county of Columbia and State of Pennsylvania, have invented certain new and useful Improvements in Saw-Mill Dogs; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

My invention relates to improvements in saw-mill dogs; and it consists in the construction, combination, and arrangement of the several parts, as will be hereinafter described and claimed.

In the drawings, Figure 1 is a perspective, and Figs. 2, 3, and 4 are side views, of my improved device, which is composed of the bracket A, the plunger B, the operating-lever C, and the pitman D, arranged and operating as will be described.

The bracket is preferably formed of the base A' and the standard A², and is provided with threaded openings a to receive feed-screws, or with other suitable means or constructions, whereby the dog and the log secured thereby may be moved forward, as is well understood. The standard A² is preferably mounted on or projected upward from the inner end of the base A'. The locking-plate B is provided on its forward edge with prongs B', which may be one in number, as shown in full lines, or two or more, as indicated in dotted lines. This plunger is provided with slots B², formed through them, and cut to provide the lower inclined portion, b; and the upper vertical portion, b', and the locking-plate and standard are secured together by the pins a', projected from the latter through the slots B², as shown. The slots B² and pins a' are so arranged that the locking-plate, when elevated, will be back from the forward edge of the standard, and the points of its prongs will be flush therewith, as shown in Fig. 3. When depressed, the forward edge of the locking-plate lies flush with the corresponding edge of the standard. As the locking-plate is depressed by the devices shown or other suitable devices, it will

be seen that its motion and that of its prongs will at first be inclined outward and downward; and that the prongs will enter the log, which is held against the dog, in a downwardly-slanting direction. The upper ends of the slots B² being vertical causes the latter part of the locking-plate's motion to be vertically downward, which causes a firm, secure bite of the prongs into the log, and a consequent stronger hold thereof than is attained by dogs of ordinary construction.

The lever C is pivoted to the standard at a point above the locking-plate and preferably in vertical line with the pins a', and is composed of the handle c and the crank portion c', bent at right angles to each other. The outer end of the crank-arm c' is pivoted to the upper end of the pitman D, which latter is pivoted at its lower end to the locking-plate at a point near the rear edge of same and midway its upper and lower ends, as shown.

When the several parts are in the position shown in Fig. 3, the device is ready for operation. The locking-plate is elevated and rests flush up against the side of the crank-arm of the lever. The log is now placed up against standard A², and the lever is drawn over to the position shown in Figs. 1 and 2. The locking-plate prongs are now embedded firmly into the log, as before described, and the end of the crank-arm is thrown forward beyond a vertical line drawn through the lever's pivot and the pivot of the plunger and the pitman, and the said end of the crank-arm bears down against the top of the locking-plate, which is thereby locked firmly in its position, as the crank-arm cannot swing farther forward, owing to the inclination of the lower portion of slots B², which will prevent the plunger, and consequently the lower end of the pitman, from moving forward. By throwing the end of the arm in advance of the lever and locking-plate pivots, as above, the involuntary movement of the lever backward is prevented, and the same is held firmly and steadily in the position shown.

In order to relieve the several parts from strain when the crank-arm is thrown forward in its locking position, I prefer to secure the stop c² on the standard in the position shown. The arm c' of the lever bears against this stop when moved forward, as shown in Fig. 2, and the breaking of the locking-plate pins a' or the

pitman or lever, when under heavy upward pressure or sudden jars, is avoided.

I prefer, instead of the stop c^2 , to employ the construction shown in Fig. 4. It consists in 5 providing the pins a' with heads a^2 , projected beyond the locking-plate, so that the pitman will bear against said heads and all forward straining will be prevented. It involves also the arrangement of the lever's pivot slightly 10 to back out of line with the pins a' , as will be understood.

In order to hold the locking-plate up in the position shown in Fig. 3, I provide the spring-bar D , secured at one end to the back of lever 15 C , and having its other end bowed, so as to engage pin d , secured on the standard, as clearly illustrated in the several views.

It will be understood that where so desired the slots B^2 could be formed in the standard 20 and the pins a' projected from the locking-plate, also that the standard could be supported without the base A' , and that such modifications would involve no departure from the principles of my improvements.

25 The locking-plate is usually made of cast-iron and the prongs of steel suitably secured to the locking-plate. The main object of my device, it will be understood, is to securely hold the last board in the operation of sawing 30 from a log.

Having thus described my invention, what I claim, and desire to secure by Letters Patent, 35 is—

1. The saw-mill dog, substantially as de- 35 scribed and shown, composed of the standard, the locking-plate having suitable prongs, and constructed with slots having upper vertical and lower inclined portions, the pins passed from the standard through said slots, the lever 40 pivoted to the standard above the locking-plate, and having its crank-arm turning down against the same, and the pitman connecting said crank-arm and the locking-plate, all sub- 45 stantially as described, and for the purposes specified.

2. The combination, in a saw-mill dog, of 45 the locking-plate, the standard, the lever, and the spring D' , having one end secured to the lever and its opposite end engaging a pin 50 secured on the standard, substantially as set forth.

3. In a saw-mill dog, the combination, with the standard and the toothed plate provided with guide-slots inclined upward and backward, and sliding upon guide-pins projected from the standard, of the lever C , pivoted on the upper end of the standard, and having the arm or extension c' projected below its pivotal center and adapted to turn inward over the upper end of the toothed plate, and the 60 pitman D , having its lower end pivoted on the rear edge of the toothed plate and its upper end pivoted to the lower end of the extension c' , the said extension and the pitman being so arranged relatively that the pivotal 65 connecting-point between them will swing to or slightly past a line drawn from the pivotal center of the lever and the pivotal center of the pitman, whereby the toothed plate will be securely locked, substantially as shown and 70 described.

4. In a saw-mill dog, the combination of the standard, the locking-plate having suitable prongs, and provided with slots having vertical and inclined wings, the pins passed from 75 the standard through the said slots, the lever pivoted to the standard above the locking-plate, the pitman connecting the lever and the locking-plate, and means, substantially as de- 80 scribed, whereby the forward movement of the lever is limited, as and for the purposes set forth.

5. In a saw-mill dog, substantially as de- 85 scribed and shown, the combination of the standard, the locking-plate provided with slots, pins a' , extended from the standard through the said slots, and having heads a^2 projected beyond the face of the locking-plate, the operating-lever pivoted to the standard above 90 the locking-plate, and the pitman connecting the crank-arm of the lever and the locking-plate, and arranged in rear of the heads a^2 and abutting thereagainst in the operation of the machine, whereby the forward movement of the 95 lever is limited, substantially as and for the purposes specified.

In testimony whereof I affix my signature in presence of two witnesses.

JOSEPH REDLINE, JR.
